UNITED STATES PATENT OFFICE.

CHARLES F. WOODS, OF PRINCETON, INDIANA.

FILM-CLAMP FOR MOTION-PICTURE REELS.

1,169,222.

Specification of Letters Patent. Patented Jan. 25, 1916.

Application filed July 12, 1915. Serial No. 39,342.

To all whom it may concern:

Be it known that I, CHARLES F. Woods, a citizen of the United States, residing at Princeton, in the county of Gibson and State of Indiana, have invented certain new and useful Improvements in Film-Clamps for Motion-Picture Reels; and I do declare the following to be a full, clear, and exact description of the invention, such as will enable others skilled in the art to which it appertains to make and use the same.

This invention relates to moving picture reels and more particularly to attachments for the hubs of said reels, which is designed to afford means whereby the end of the film may be easily, conveniently and quickly connected with, or disconnected from the reel.

A further object of the invention is to provide a device which is simple and durable in construction, inexpensive to manufacture and one which will be very efficient in operation.

With these and numerous other objects in view my invention consists of certain novel features of construction, combination and arrangement of parts which will be herein referred to and more particularly pointed out in the specification and claims.

In the accompanying drawings: Figure 1 is a side elevation of my improved fastening device for film reels with one of the end plates removed from the hub; Fig. 2 is a top plan view of the reel showing my improved fastening means applied to the hub; Fig. 3 is a vertical transverse section through the reel on the line 3—3 of Fig. 1; Fig. 4 is a central vertical longitudinal section through the hub of the reel taken on the line 4—4 of Fig. 2; Fig. 5 is a plan view of the cover of my attachment which is applied to the hub of the reel; Fig. 6 is a plan view of one of the levers of this device.

In describing my invention I shall refer to the drawings by similar reference characters which designate corresponding views throughout the several parts and in which the letter R designates a film reel used in connection with motion picture machines, and is of the ordinary construction used in making reels of that character. The hub H of said reel may be made of wood or any other desired material, and is formed with an axial opening 1 therethrough and with counter-sinks 2 for the heads of the screws by which the disks or ends of the reel are secured to the hub.

The hub H has formed in its outer periph-

ery a recess 3 which is formed as clearly shown in Fig. 4 of the drawing. This recess 3 is adapted to be covered by a metallic strip 4 of the shape shown in Fig. 5 of the drawings, which is adapted to cover the same and is secured to the hub by apertured lugs or ears 5 formed on either side thereof and bent at right angles to the cover 4 to engage sockets 6 in the sides of said hub. When in this position, nails, or screws as shown at 7, or any other preferred form of locking means are inserted through the apertures in the lugs or ears 5 to secure the cover firmly to the hub. This cover 4 is bent to conform substantially to the curvature of the outer periphery of the hub, and when in position forms a complete cover for the recess 3 therein. A central aperture 7', and a pair of transversely extending slots 8 at diametrically opposite points are formed through said cover for a purpose to be hereinafter more fully described.

The gripping means of this device consist of a pair of operating levers 9 which have enlarged heads 10 at one end to form shoulders 11 thereby, and the other end of said levers 12 being curved arcuately to conform substantially to the outer periphery of the hub H. The enlarged heads of these levers 10 have their outer extremities 13 depending or bent downwardly at right angles to the said levers. When it is desired to position this device the levers 9 have their ends 12 inserted through the slots 8 in the cover 4 until the shoulders 11 of said levers abut against the under side of the said cover. When in this position the enlarged heads 10 of the said levers will be positioned beneath the cover 4 with their outer extremities 13 engaging with each other, and positioned beneath the central apertures 7 in the said cover 4, as clearly shown in Fig. 4 of the drawings.

A coiled spring 14 is positioned in the recess 3 of the hub in such a manner that the lower end of said spring rests in the bottom of the recess, and its upper end engages the lower surfaces of the enlarged heads 10 of the levers 9. The depending abutting extremities 13 of the said heads are adapted to form a guard or positioning member for said spring when the parts are assembled in the positions above described.

It will be noted that the levers 9 owing to the fact that the shoulders 11 thereof engage the lower surface of the cover 4 adjacent either end of the slots 8 are fulcrumed at

that point, so that while they are normally held in the position shown in Fig. 4 of the drawings, by reason of the upward pressure of the coiled spring 14, any downward pressure upon the heads 10 of the said levers will cause the projecting curved ends 12 of the same to be lifted from out of engagement with the outer periphery of the hub.

Thus it will be seen by reason of the above 10 described operation when the parts of this device are assembled when it is desired to attach the end of a film to the hub it is only necessary for the operator to insert a finger through the aperture 7 in the cover 4 on the 15 hub, and press downwardly therethrough whereupon the heads 10 of the levers 9 will be moved inwardly, and owing to the fact that the said levers are fulcrumed at a point intermediate their ends, the outer ends 12 20 of the levers will be lifted from out of engagement with the outer periphery of the hub H, so that the film may be inserted therebetween at either end. Upon removing the finger from the opening 7 the pressure upon the enlarged heads 10 of the levers will be released, and the coiled spring 14 which has been compressed during the 25 above described operation will expand thereby returning the heads 10 to their normal position into engagement with the lower surface of the cover 4, which will throw the ends 12 of the levers back into engagement with the outer periphery of the hub, thereby 30 forming a secure and firm gripping 35 means for the end of the film.

This attachment for hubs of film reels enables the film to be conveniently attached thereto from either end by means of the movable clamping ends 12 of the levers, 40 without any danger of the ends of the films becoming torn during the gripping operation. This attachment forms a quick connecting or disconnecting means for films and obviates the danger of tearing the ends 45 of the same during the connecting or disconnecting operation, which is a great advantage in devices of this character as is well known to those skilled in the operation of motion picture machines.

50 From the foregoing description of the construction of my improved hub attachment for film reels the manner of applying the same to use and the operation thereof will be readily understood and it will be seen that I have provided a simple, inexpensive and efficient means for carrying out the objects of this invention.

I claim as my invention:

60 1. A device of the character described including a hub with a recess in its outer periphery, a covering for said recess having a finger opening and a slot therethrough, a lever fulcrumed intermediate its ends, a

portion of the lever projecting through said slot to engage the outer surface of said hub, 65 and the other portion of said lever positioned in the recess below the finger opening.

2. A device of the character described including a hub with a recess in its outer periphery, a covering for said recess having a finger opening and a slot therethrough, a lever fulcrumed intermediate its ends extending through said slot, the portion of the lever projecting through said slot being 70 curved to engage the outer surface of the hub, an enlarged head formed on the other portion of said lever positioned in the recess, and a spring in said recess below the 75 enlarged head of the lever.

3. A device of the character described including a hub with a recess in its outer periphery, a cover for said recess having a central opening therethrough, a pair of oppositely extending fulcrumed levers having 80 one end portion positioned in said recess and registering with the opening in the cover, and the other end portion of said levers extending through the cover to engage the outer surface of the hub.

4. A device of the character described including a hub with a recess in its outer periphery, a cover for said recess, a pair of oppositely extending levers with enlarged 95 abutting heads positioned in said recess, the other portion of said levers extending through the cover at diametrically opposite points and engaging the outer surface of said hub, a spring positioned in said recess below the abutting heads of the levers, and 100 said cover having a finger opening above the same.

5. A device of the character described including a hub having a recess in its outer periphery, a circumferentially extending 105 covering for said recess having a central opening therethrough, means to secure said covering to the hub, said covering having a pair of diametrically opposed laterally extending slots therethrough, levers fulcrumed intermediately of their ends extending through said slots and curved to engage the outer surface of the hub, enlarged heads with depending abutting extremities on the portions of the levers in 110 said recess, and a coil spring positioned between the enlarged heads of said levers and the recess.

In testimony whereof I have hereunto set my hand in presence of two subscribing witnesses.

CHARLES F. WOODS.
